MACHINE FOR AFFIXING OPENING
THREADS TO SEALED CONTAINERS

Harry J. Engle, Otto J. Gaedig and Russell T. Henneberry, St. Louis, and Lester W. Uhles, Maplewood, Mo., assignors to Sefton Fibre Can Company, Maplewood, Mo., a corporation of Delaware

Application December 27, 1938, Serial No. 247,784

25 Claims. (Cl. 93—40.1)

This invention relates to machines for making container bodies of the kind having separate sections that are held together by a seal, label or wrapper adapted to be broken along the joint between said sections to permit separation thereof, and it relates more particularly to machines of the type wherein the sectional body is formed by winding strips of adhesive paper in a number of convolutions around a rotary mandrel and the sealing label or wrapper is wrapped around the convolute shell or body as it rotates with said mandrel. The invention has for its principal object to provide a machine of the above type that will apply an opening thread beneath the label or seal at the joint between the two container sections, with one end of the thread left exposed so that said seal or label may be broken at said joint by pulling on the exposed end of the thread. Other objects are to provide for the interchange of the label affixing table of said machine with a combined label and thread affixing table; to provide for accurately locating the thread in line with the joint between the body sections on the mandrel; to utilize the rotary movement of the body supporting mandrel for wrapping the thread around the body while the seal or label is being affixed thereto; to provide for adjustment of the parts for container bodies of different shapes and sizes; to provide for the operation of the thread laying, affixing and cut-off mechanism in proper timed relation with the body forming and label affixing mechanism; and to provide for simplicity and cheapness of construction and to obtain other advantages herein-after appearing. The invention consists in the thread affixing mechanism and in the construction and combinations and arrangements of parts hereinafter described and claimed.

In the accompanying drawings, which form part of this specification and wherein like symbols refer to like parts wherever they occur:

Fig. 1 is a front side elevation of the label affixing or delivery end portion of a convolute winding and labeling machine provided with a thread affixing mechanism embodying my invention.

Fig. 2 is an end elevation of said portion of said machine,

Fig. 3 is a vertical transverse section on the line 3—3 in Fig. 1,

Fig. 4 is a rear elevation of the label supporting table and thread laying and cut-off mechanism, as indicated by the line 4—4 in Fig. 3,

Figs. 5 and 6 are vertical transverse sections

through said table on the line 5—5 and 6—6, respectively, in Fig. 4.

Fig. 7 is an enlarged fragmentary front elevation of the lower portion of the machine, showing the cam actuated switches and valve for controlling the sequence of operation of thread laying, cut-off and gripping device.

Figs. 8 and 9 are vertical cross sections on the lines 8—8 and 9—9, respectively, in Fig. 7.

Fig. 10 is an end elevation of the combined label and thread affixing table.

Fig. 11 is a perspective view of the notched solenoid actuated plate for raising and lowering the thread laying and cut-off device in the retracted positions thereof.

Fig. 12 is a fragmentary rear elevation of the combined label and thread fixing table.

Fig. 13 is a fragmentary vertical cross-section through the thread gripping mechanism on the line 13—13 in Fig. 12.

Figs. 14 and 15 are sections through one of the thread gripping devices on the line 14—14 in Fig. 13, showing said device in closed and open positions, respectively.

Fig. 16 is a fragmentary horizontal section on the line 16—16 in Fig. 12.

Fig. 17 is a vertical transverse section through the table on the line 17—17 in Fig. 12.

Fig. 18 is a plan view of the supporting block for one of the thread gripping devices.

Fig. 19 is a side view of said block, looking at the table opposing side thereof.

Fig. 20 is a fragmentary perspective view of one of the thread laying devices, the thread cut-off device associated therewith and the supporting bar for said devices.

Fig. 21 is a vertical cross-section through said devices on the line 21—21 in Fig. 20.

Fig. 22 is a vertical transverse section along the longitudinal axis of the thread cut-off device on the line 22—22 in Fig. 20.

Fig. 23 is a similar section through the thread laying device on the line 23—23 in Fig. 20.

Fig. 24 is a perspective view of the supporting bar for the thread laying and cut-off devices in the region of the outermost end frame of the table, showing the cut-off knife actuating shaft, the actuating arm therefor and the spring device for holding said knife in raised or inoperative position.

Fig. 25 is a vertical cross-section through said bar and said spring device on the line 25—25 in Fig. 24.

Fig. 26 is a vertical cross-section through the thread laying device on the line 26—26 in Fig. 20.

Fig. 27 is a diagram showing the electric circuit for controlling the solenoid for opening the thread gripping device, the solenoid for operating the thread cut-off device, the solenoid for raising said devices in the retracted position thereof and the fluid cylinder and cam controlled valve for projecting and retracting said devices.

Figs. 28, 29, 30 and 31 are fragmentary diagrammatic views of the label and thread affixing table and the mandrel upon which the convolute container shell is formed, the several views showing the various positions assumed by the thread laying, gripping and cut-off devices during the operation of applying the label and opening thread to the said container.

Fig. 32 is a similar view showing the relative positions of the mandrel label smoothing roller and thread laying and cut-off devices while the mandrel is being rotated to wrap the thread and label around the container.

Fig. 33 is a side elevation of the finished container shell with the connecting or sealing label and opening thread applied thereto; and

Fig. 34 is an enlarged fragmentary section 25 through said container shell on the line 34—34 in Fig. 33.

In the accompanying drawings our invention is illustrated in connection with a machine for making tubular container bodies of the kind 30 having separately formed sections 1 and 2 that are secured together in endwise abutting relation by a seal, label or wrapper adapted to be broken along the point 3 between said sections to permit separation thereof. In this type of 35 machine, the sectional container body is formed by winding two strips of adhesive paper side by side in a number of convolutions around a mandrel 4 by rotating the latter about its longitudinal axis while the paper is held against the 40 rotating mandrel by a suitable pressure roller 5. After the mandrel 4 is rotated the desired number of revolutions, depending on the number of convolutions desired, the mandrel is stopped and the convolute shells or container sections 1 45 and 2 are slid endwise along the mandrel to a label applying station by means of a suitable stripper 6 that embraces the mandrel and is slid therealong by means of a suitable shifter fork 7. In this position of the convolute shells 50 the label is pressed against the adhesive outer surfaces thereof and the mandrel is again rotated to cause the label to wind around said sections and thus hold them together in abutting endwise relation. During this rotary movement of the 55 mandrel, the label is held against the two shells joined thereby by means of a suitable pressure roller 8. After the application of the label the finished container body is pushed off the end of the mandrel by the sliding movement of the 60 succeeding shells into labeling position.

The mandrel is suitably supported and intermittently rotated in any desired manner (not shown). As shown in Figs. 1 and 2, the respective pressure rollers 5 and 8 are controlled by edge 65 or disk cams 9 and 10 fixed to continuously rotating main drive shaft 11 that extends longitudinally of the machine. The cam 9 engages a roller 12 journaled on one end of a lever 13 that is pivoted on the frame 15 of the machine and 70 has a spring connection 14 therewith for holding said roller in contact with said cam. The other end of said lever is connected to the lower end of a rod 16 whose upper end is connected to a lever 17 that is journaled for vertically swinging movement in a bracket 18 and has the pressure roller

5 suitably supported thereon. As shown in Fig. 2, the pressure roller 8 is mounted on the upper end of an arm 19 whose lower end is fixed to a horizontal rock shaft 20 which is journaled in the frame 15 and has a rock arm 21 rigid therewith whose free end is provided with a roller 21a that is held in engagement with the cam 10 by a spring 22 being attached at one end to the frame and at the other end to the arm 19.

As shown in Figs. 1, 2 and 3, the continuously 10 rotating drive shaft 11 has a gear 23 thereon that intermeshes with a gear 24 journaled on a countershaft 25 that is journaled in frame 15 and is connected to a table 26 adapted to support one or more stacks of the labels 27 and to move upwardly 15 (see Figs. 29 and 30) to press the uppermost label into engagement with the shell located thereabove. The table 26 is mounted on the upper end of a plunger 26a that is mounted for vertically reciprocating movement in a cylinder 28 provided therefor in the frame 15 of the machine. This plunger is provided on one side with a rack 29 adapted to be engaged by a pinion 25a fixed to the intermittently driven shaft 25. This shaft is operatively connected to the continuously 20 driven gear 24 by means of a suitable clutch comprising cooperating friction disk elements 30 and 31 on the shaft and driven gear, respectively. The movable clutch element 30 is splined on the shaft 25 and is engaged with the clutch element 30 of the gear 24 by means of a compression coil spring 32 sleeved on said shaft between a nut 33 thereon and a shifter arm 34 through which said shaft extends. One end of this arm is pivotally supported on a rod 35 fixed to the frame 15 of the 35 machine; and the other end of said arm has a roller 36 journaled thereon adapted to cooperate with a face cam 37 fixed to the continuously rotating drive shaft 11. By this arrangement, the clutch is engaged by the spring 32 to raise the 40 table 26 once during each revolution of the drive shaft 11; that is, when the roller 36 and the cam 37 enters the drop 37a in said cam, said table being returned by its own weight to its lowermost position. 45

The automatic convolute shell forming and label applying machine thus far described is well known and it is considered unnecessary to illustrate it in detail.

In accordance with the present invention, the 50 hereinbefore described container body forming and labeling machine is provided with means for applying an opening thread 38 (see Figs. 33 and 34) between the label and the container sections 1 and 2 at the joint between said sections, with 55 one end 38a of said thread left loose and exposed so that a pull thereon will cause the thread to break said label along said joint and thus permit separation of the said sections. As shown in the drawings, the thread affixing means includes 60 duplicate upright frames 39 whose lower ends are provided with ribs 40 that are slidable in horizontal grooves 41 in the respective ends of the table 26 and secured thereto in the desired position of adjustment by means of cap screws 41a. 65 The two end frames are connected at their upper ends by means of a horizontal top frame member comprising end portions 42, which have ribs 43 slidable in longitudinal grooves 44 provided therefor in the tops of the respective end frames 70 39 and are connected at their mandrel opposing ends by a web or bar 45. The end portions 42 of the top frame are secured in the grooves 44 of the end frame members of the table by means of cap screws 46. 75

Rigidly secured to the innermost end frame of the table 26 is a fluid cylinder 47 containing a piston (not shown) having an upwardly and rearwardly extending rod 48 whose outer end is pivotally connected, as at 49, with the outer end of one arm of a lever 50 fixed to a rock shaft 51 journaled at and intermediate between its ends in suitable bearings 52, 52a provided therefor on the end and web members 43 and 45, respectively of the top frame. The other arm of the lever 50 extends downwardly outside of the adjacent end frame 39 and is pivotally connected, as at 54, to a lever 55 substantially intermediate between the ends thereof. One end of this lever 55, the end remote from the mandrel 4, has a cam roller 56 journaled thereon which works in a horizontally extending cam slot 57 formed in a plate 58 that is removably secured to the innermost end frame 39 of the table 26. The mandrel opposing end of this cam slot is curved upwardly, as at 59, and the other end of said slot is extended downwardly as at 60. Fixed to the shaft 51 beyond the outermost end frame 39 of the table 26 is a downwardly extending arm 50a similar to the downwardly extending arm of the cylinder operated lever 50; and a lever 55a similar to the lever 55, is pivotally supported, as at 54a intermediate between its ends on the lower end of the arm 50a. The lever 55a, like the lever 55 is provided at the end thereof remote from the mandrel with a cam roller 56a which works in a cam slot 57a formed in a plate 58a that is removably secured to the outermost end frame of the table and has its mandrel opposing end 59a curved upwardly after the manner of the corresponding end of the cam slot 57 in the removable plate 58 on the innermost end frame of the table. The other end of cam slot 57a opens into an opening 60a that extends above and below said slot. Supported on and secured to the mandrel opposing ends of the levers 55 and 55a is a cross bar 61 adapted to support one of more thread laying and thread cutoff devices.

As shown in Fig. 20, each thread laying or positioning device comprises a finger 62 removably mounted on the cross bar 61 and extending crosswise thereof in the direction from the mandrel 4. This finger has a tapered or wedge shaped outer end portion 63 and has its inner end portion grooved crosswise on its under side to straddle the cross bar 61 to which it is rigidly clamped by means of a cap screw 64 that extends downwardly through said finger and a longitudinal slot 65 provided therefor in said bar and is threaded into a clamp plate 66 that bears against the under side of said bar and has a transverse guide rib 67 that seats within said slot. By this arrangement the finger 62 may be shifted longitudinally of the cross bar 61 and clamped thereon in the desired position of adjustment by tightening the clamp screw 64. Removably secured to the underside of the finger 62 by means of cap screws 68 is a base plate 69 having a tapering outer end portion 69a that terminates beyond the edge thereof in a blunt end 69b, thereby forming a ledge 70 around the sides and end of said wedge shaped portion of said finger. The upper portion of the finger is cut away, as at 71, along one side and across the wedge shaped end thereof to accommodate a thread hold-down block 72. This block seats flatwise upon the bottom of the cut-away portion 71 of the finger and has a wedge shaped outer end portion 72a whose sides are in flush

alignment with the sides of the wedge shaped end 63 of said finger. The rear end of the hold-down block 72 is secured by a horizontal pivot 73 to the finger 62 and is yieldably held down on said finger by means of a leaf spring 74 and is provided beyond the free end of said leaf spring with a pin 75 whereby said block may be swung upwardly to facilitate threading, after having swung said spring laterally clear of said block. The under side of this hinged hold-down plate 72 is provided with a downwardly opening central longitudinal groove 76 which cooperates with the portion of the finger located therebelow to form a passageway for the thread. As shown in Fig. 23, the thread, just before entering the groove 73 passes beneath the tapered lower end of a dog 77 whose upper end is supported on a horizontal pivot 78 that is fixed to an upstanding lug 79 on the finger and is disposed crosswise thereof. The lower end of this lug is yieldably held down on the thread by means of a tension spring 77a having one end fixed to said lug and the other end fixed to the fixed pivot pin 78 permits travel of the thread towards the outer end of the finger but prevents movement of the thread in the opposite direction. The thread passes through a guide slot provided therefor in an upstanding pin 80 mounted on the finger forwardly of the dog 77 and through a guide 81 on a bracket 82 that is supported on top of the cross bar 61 and has a transverse rib 83 on its underside that seats in the slot 65 in said bar, whereby said bracket may be adjusted longitudinally of said slot. The bracket 82 is rigidly secured to the cross bar in the desired position of adjustment longitudinally thereof by means of a cap screw 83a which extends downwardly through said bracket and the slot in the cross bar and is threaded into a clamp plate 84 that bears against the under side of said cross bar 40 and has a transverse rib 85 on its upper side that slidably engages the slot therein. The thread thence passes through a guide 86 fixed to the main frame 15 of the convolute winding machine to a source of supply comprising a spool 87 of 45 thread sleeved on an upright spindle 88 supported on a bracket 89 that projects horizontally from said frame.

Each thread cutoff device (see Figs. 20 and 23) comprises an arm 90 that is supported on 50 and is adjustable longitudinally of a rock shaft 91 that extends longitudinally of and is supported on the cross bar 61. This arm has a split hub portion that is clamped to the shaft 91 by means of a clamp screw 92. The shaft 91 is 55 journaled in suitable bearing blocks 93 that seat on top of the cross bar 61 and have transverse ribs 94 on their under sides that seat within the elongated slot 65 in said cross bar. These blocks are secured to the cross bar by means of cap 60 screws 95 that extend downwardly through said blocks and the slot 65 in said bore with their lower ends threaded through clamp plates 96 that bear against the under sides of said bar and have transverse ribs 97 on the upper surface that 65 slidably fit said slot.

The arm 90 extends outwardly from the cross bar 61 along side of the finger 62 in the direction of the mandrel 4 and has a tapered, axially bored, externally threaded split outer end portion 98. Mounted on this portion 98 of the arm 90 is a clamp sleeve 99 that has a threaded bore that is adapted to receive said portion of said arm and has a flared end adapted to seat against the tapered portion of said arm. Mounted in 75

- the bore of this sleeve is a spindle 100 whose inner end portion is disposed in the bore of the split portion 98 of the arm 90, whereby said spindle is rigidly clamped to said arm against both axial and rotary movement when said sleeve is tightened to cause said split portion of said arm to grip said spindle. The spindle 100 projects beyond the outer end of the sleeve 99 and has a knife blade 101 secured thereto with its cutting edge disposed opposite the blunt end 69b of the base plate 69 of the thread laying finger 62 in a position to swing across said end after a manner of a shear to cut the thread flush with said blunt end of said bottom plate.
13. As shown in Figs. 24 and 25 the knife supporting arm 90 is normally held in raised or inoperative position by means of a coil compression spring 102 interposed between the corresponding ends of a pair of plates 103 and 104 disposed crosswise of the cross bar 61 one above and the other below said bar. The upper plate 103 is clamped to the knife actuating shaft 91 by means of a clamp screw 105, one end of this plate projecting beyond the mandrel opposing side of the cross bar and having a recess on the under side thereof adapted to form a seat for the upper end of the spring 102; and the other end of said plate is adapted to bear against the upper surface of said cross bar and limit the upward swinging movement of the knife. An operating arm 106 has a split hub portion secured to the shaft 91; and projecting by means of a clamp screw 107 laterally from the outer end of said arm is a pin 108.
35. The arm 106 is swung upwardly against the tension of the spring 102 to swing the knife 101 downwardly across the blunt end 69b of the thread positioning finger 62 preferably by means of a pull type electromagnet or solenoid 109 having a downwardly extending plunger or armature 110 which terminates at its lower end in an inclined surface 110a adapted, when the solenoid is energized, to swing said arm upwardly and thus rotate the shaft 91 in a direction that will swing said knife downwardly into an operative position. The frame 111 of this solenoid is removably secured by means of cap screws 112 to a horizontal bar 113 that is removably secured to the outermost end frame of the table 26. This bar is provided with an elongated slot 114 through which the screws 112 extend; and the solenoid frame 111 is provided with vertical slots 115 through which the said screws also extend, whereby the solenoid is adjustable both horizontally and vertically with respect to the table and mandrel.
- When the two cross bar supporting levers 55 and 55a which are pivotally suspended intermediate to their ends on the arms 50 and 50a of the cylinder operated rock shaft 51, are in retracted position, the cam roller 56a carried by the lever 55a enters a lateral opening notch 116 formed in a plate 117 that is mounted for vertical sliding movement in the enlarged opening, 60a at the end of the cam slot 57a in the cover plate 58a on the outer end frame of the table. This plate is normally held by means of a coil spring 118 in the uppermost position of its sliding movement with its notch in register with and forming a continuation of the cam slot 57a in the cover plate 58a. The plate 117 is suitably secured to and forms part of the armature or plunger 119 of an electromagnet or pull type solenoid 120 that is secured to the adjacent end of the table by means of cap screws

121. The armature slides between guide plates 122 fixed to the plate 58a; and the solenoid frame has a rib slidable in the groove 40 in the adjacent end of the table. When the solenoid 120 is energized, the plunger 119 is pulled downwardly against the tension of the spring 118 and the roller 56a on the lever 55a being in engagement with the notch 116 is pulled downwardly with said plunger and causes said lever to turn on its pivot 54a and swing its front thread laying and cut-off mechanism supporting end upwardly. This same swinging movement is imparted to the other lever 55 in the retracted position thereof, downwardly extending end 60 of the cam slot 57 permitting such movement of said lever.

When the piston in the cylinder 47 is drawn inwardly therein, the two cross bar supporting levers 50, 50a swing in the direction of the mandrel and thus shift the two levers 55, 55a in the direction of the mandrel. In this position of the parts, see Fig. 28, the thread is carried by each thread laying finger 62 beneath the mandrel into engagement with a suitable thread holding or gripping device adapted to seize the exposed loose end 38b of the thread on the edge at the outer end of said finger. As shown in Figs. 12 to 17, this thread holding device preferably comprises a pair of jaws 123 that are pivotally secured together and to the upper end of a supporting block 124 by an upstanding pivot pin 125 on said end of said block and are adapted to be brought together to clamp the thread therebetween. The two jaws 123 are normally held in closed position by means of a U-shaped spring 126 which straddles the pivoted ends of said jaws with its ends seated in notches 127 in the outer faces thereof. The block 124 is secured flatwise to the rear face of a plate 128 that is mounted for vertical sliding movement on the rear side face of the table 26. Said block is secured to said plate by means of a cap screw 129 which extends horizontally therethrough into an elongated slot 130 in the vertically slidable plate 128 and is threaded into a clamping plate 131 that is slidable longitudinal in said slot, both the block and the plate being provided with horizontal ribs 132 and 133, respectively, that are slidable in said slot. As shown in Figs. 12, 16 and 17, the vertically slidable threaded grip supporting plate 128 has its ends disposed in vertical guideways formed by plates 134 secured to the table in overlapping relation to the ends of said slide plate. This slide plate 128 is suspended for downwardly yielding movement relative to the table by means of coil springs 135 whose lower ends are connected to lugs 128a at the lower corners of the slide plate and whose upper ends are secured by means of cap screws 135a to the guide plates 134.

The thread gripping jaws 123 are swung open against the tension of the closing spring 126 therefor by means of a rotary face cam 136 located in a recess 124a provided therefor in the block 124 beneath said jaws. This cam works between rollers 137 journaled in the opposing sides of the thread gripping jaws 123 and are adapted in engagement with the rise of the cam 136 to force said jaws apart into thread releasing position. When the drop of the cam is opposite the rollers 137 the jaws are closed by the spring 126. As shown in Fig. 13, the thread gripping jaws are disposed at a downwardly and rearwardly inclination with respect to the table, with their thread gripping ends facing the latter. 75

in the projected position of the thread laying finger said finger is disposed at an angle corresponding to the angle of the thread locking jaws with its wedge shaped end portion 63 disposed in the gap between the thread engaging ends of said jaws, and the tapered base plate 69 centers itself within a correspondingly tapered recess 124b provided therefor in the inclined upper face of the supporting block 124. The cam 136 is fixed to a horizontal rock shaft 138, which is journaled in the block 124 and in a bracket 139 that is fixed to the downwardly yielding block supporting plate 128 and extends beyond the rear end frame of the table. As shown in Figs. 12 and 17, this bracket forms a housing for a pinion 140 on the shaft 138 and has an opening extending therethrough at right angles to the pinion axis for slidably supporting a rack bar 141. The rack bar has a coil compression spring 142 sleeved thereon between a collar 143 thereon and the bracket 139, which spring serves to shift said rack bar in a direction that will rotate the cam 136 to a position that will permit the spring 126 to close the thread gripping jaws 123.

25 The rack bar 141 is shifted in the opposite direction to rotate the cam 136 to a position that will open the thread gripping jaws 123 by means of a plunger type electromagnet or solenoid 144 which is secured by means of cap screws 145 to the rear end of the table. The frame of the solenoid has a rib slidable in the supporting slide-way 40 for the outermost end frame of the table, thereby permitting adjustment of the solenoid frame towards and away from the rock shaft 138.

30 The armature 146 of this solenoid 144 has a slot-and-pin connection with the rack bar 141 that permits relative vertical movement of said armature and rack bar, said slot-and-pin connection comprising a pin 147 on the armature that works in a vertical slot 148 provided therefor in the rack bar.

35 Mounted on the base of the machine below the table 26 is a horizontal shaft 149 that is continuously driven from the continuously rotating shaft 11 through a sprocket chain 150. This shaft has an edge cam 151 fixed thereto adapted to actuate the operating arm 152 of a suitable valve 153 which controls the admission of air to and the exhaust of air from the cylinder 47 that shifts the thread laying finger 62 towards and away from the mandrel 4. The connections between the valve and the cylinder comprises a conduit 154 leading from the valve to one end of the cylinder and a conduit 155 leading from the valve to the other end of the cylinder. Air is supplied to the valve 153 by suitable conduit 153a. The continuously rotating valve operating shaft 149 also operates three switches A, B and C for controlling the solenoids 109, 120 and 144. As shown in Figs. 7 and 8, these switches, which may be of any desired construction, each preferably comprises a stationary contact member 156 carried by a disk 157 through which the shaft 149 extends and a movable contact arm 158 that is movable into and out of engagement with the stationary contact by a cam 159 fixed to said shaft. As shown in Figs. 7 and 8, the disk 157 carries the stationary contact 156 and is mounted for vertical adjustment on a pair of posts 160 located one on each side of said shaft, said disk being provided with split lugs 161 that are clamped to the posts by means of clamp screws 162. The movable contact carrying arm 158 is pivotally mounted on an insulating plate 163 fixed to the disk 157 and is provided with a binding

post 164 that is connected to the movable contact by means of a spring plate 165. The metal disk 157 also carries a binding post 166; and the cam 159 is fixed to the shaft 149 in the desired position of angular adjustment by means of a set 5 screw 167. As shown in the wiring diagram in Fig. 27, the wires of the electric circuit lead from a source of electrical energy and are connected with the respective binding posts of the switches for controlling the solenoids, the relative angular position of the cams on the shaft 149 bringing about the operation of the solenoids in proper sequence and the angular position of the valve operating cam 151 on said shaft bringing about the operation of the piston in the cylinder 47 in 10 proper timed relation with switch operating cams. As shown in Fig. 27, the cams which control the switches for the solenoids 109 and 120 are each provided with one flat face that permits the switch to close once only during each revolution 20 of the shaft 149; whereas the cam which operates the switch for the solenoid 144 that opens the thread gripping jaws 123 has two flat faces which permit the solenoid to be energized twice during each revolution of the cam. While the 25 jaws 123 are required to open and close once only during each revolution of the cam, the two flat faces are provided to energize the solenoid twice during each revolution of the switch controlling cam in order to shorten the length of 30 time during which the jaw opening solenoid 144 is energized and thus prevents said solenoid from becoming overheated and burning out.

35 The operation of the machine is as follows: The convolute cardboard shell sections 1 and 2 35 formed on the mandrel 4 are shifted endwise thereof to label receiving position, and the table 26 is raised to bring the label 3 on top of the stack carried by said table into contact with the two abutting shells, all in accordance with previous practice and in the manner hereinbefore described. With the present invention, however, just before the table is raised to bring the label into engagement with the shell sections on the stationary mandrel, the cam 151 on the continuously driven shaft 149 operates the valve 153 to supply air to the cylinder 28 to shift the piston therein in a direction that will cause the two levers 55, 55a to move in the direction of the mandrel. Near the end of this movement, the 45 cam rollers 56, 56a move upwardly into the upwardly curved portions 59, 59a of the cam slots 57, 57a and thus cause the opposite ends of said levers to swing downwardly about their pivots 54, 54a and slide the wedge shaped end of the 50 thread laying finger 62 between the open thread gripping jaws 123 and the tapered end of the base plate 69 of said finger into the beveled tapered guide pocket 124b of the jaw supporting block 124 (see Fig. 28). The jaw opening solenoid 144 55 is then deenergized, thereby permitting the spring 142 to rotate the cam 136 to a position that will permit spring 126 to close the jaws upon the exposed loose end 38b of the thread lying on the shelf 70 formed by the projecting blunt end 69b 60 of the base plate 69.

65 Air is then supplied by the valve 153 to the opposite end of the cylinder 47 to shift the levers 55, 55a in a direction that will retract or withdraw the thread laying finger 62 from beneath the mandrel. The table 26 then moves upwardly to bring the uppermost label into contact with the bottom of the convolute shells on the mandrel thereabove; and, at the same time, the ends of the downwardly yieldable thread 70 75

lock carrying plate 128 engage the mandrel thereby causing the ends of the closed thread jaws to move below the level of the compressed stack of labels (see Fig. 29). The solenoid 120 is then energized to pull the armature 119 thereof and the notched plate 117 downwardly, whereby the end of the lever 55a having the cam roller 56a seated in the notch 116 in said plate is swung downwardly and the opposite end which 10 carries the thread laying finger 62 is swung upwardly to take up any slack in the thread between the closed thread holding jaws 123 and said finger (see Fig. 30). The movable clutch element 30 is then disengaged from the continuously driven gear 24 thereby permitting the table to move downwardly, and the solenoid 144 is energized to open the thread gripping jaws 123 and release the thread. The solenoid 109 is energized to pull its armature 110 upwardly 20 and force the inclined surface 110a at the lower end thereof into engagement with the under side of the pin 108 on the operating arm 106 of the rock shaft 91, thereby rotating said shaft against the tension of the spring 102 in a direction which 25 will cause the knife 101 to swing downwardly across the blunt edge 69b of the base plate 69 of the thread laying finger 62 and thus sever the thread at said edge (see Fig. 31). With the parts in this position the mandrel is rotated to 30 cause the label 3 to wrap around the abutting shells 1 and 2 and adhere thereto with the assistance of pressure roller 8 (see Fig. 32).

The hereinbefore described machine permits the thread laying finger and the thread gripping jaws to be shifted longitudinally of the mandrel to bring the thread in accurate alignment with the joint between the two container shells. The entire thread laying and cut-off mechanism may be shifted toward and away 40 from the mandrel by shifting the end frames 39 crosswise of the table. The time of the thread cutoff may be varied for shells of different widths by the use of cover plates 58, 58a having cam slots of different length and shape, and the timing of the operation of the different solenoids 45 may be regulated by adjusting the relative angular positions of the rotary cams which operate the switches that control the respective solenoids. The yieldable mounting of the thread gripping device permits the entire device, including its cam shaft and the rack and pinion therefor, to move downwardly below the level of the label stack when the stack is pressed against the under side of the mandrel and to 50 move above the stack when the pressure thereon is released to permit the thread gripping jaws to rise above the level of the labels in position to receive the thread laying finger as it moves thereacross.

60 The present label and thread affixing table may be used interchangeably with the old label fixing table merely by removing the new table and substituting the old table therefor, thereby adapting the machine for use in applying labels in accordance with the old practice. When the machine is operating with the old table, the control valve for the finger shifting cylinder is shut off to prevent the escape of air therefrom by 65 means of a horizontal slidable push-and-pull rod 168 which is pressed against an arm 168a fixed to the shaft on which the cam actuated operating arm 152 of the valve is secured, to hold said arm 152 clear of the rotating cam 151, said rod 70 having a notch 169 thereon adapted to engage

a lug 170 on the frame of the machine (see Figs. 1 and 2).

While the invention is particularly adapted for use with a convolute winding machine of the type shown and described, it may also be embodied in other types of container forming and labeling machines or embodied in a separate independent machine, and we wish the word "label" to be taken broad enough to cover all forms of wrappers or seals for releasably holding together separable container sections. Obviously the construction hereinbefore described admits of considerable variation without departing from the invention.

What we claim is:

1. In a machine for affixing a label to a container, a support for said container, a support for said label located below the support for said container, means for imparting relative vertical movement to said supports to engage said label with said container, and means for affixing a label rupturing thread to said container, said means comprising a single thread gripping member mounted on said label support at one side of said label, and a single thread carrying member mounted on said label support adjacent to the opposite side of said label to move through the space between said container and said label into engagement with said single gripping device to engage the thread therewith and to return to a position clear of said space prior to the engagement of said label with said container.

2. In a machine for affixing a label to a container body, a support for said container, a support for said label below the container support, means for raising the label support to engage the label thereon with the underside of said container, and means for affixing a thread to said container for rupturing said label, a supply mass of thread, said means comprising a thread gripping member mounted on said label support at one side of said label, and a member mounted on said label support adjacent to the opposite side of said label for movement between said container and said label for withdrawing thread from said supply mass and for laying the loose end of said thread in said thread gripping member, said thread laying member being movable into and out of its thread laying position beneath said container support prior to the engagement of said label with said container by the upward movement of said label support, and means associated with said thread laying member for severing said thread adjacent to the forward end of thread laying member upon its return from thread laying position beneath said label support to a position clear thereof.

3. In a machine for affixing a label to a container, a support for said container, a support for said label, means for imparting relative movement to said supports to affix said label to said container, and means for affixing an opening thread to said container comprising a thread gripping member, a thread carrying member movable between said container and said label into and out of engagement with said thread gripping member for inserting the thread therein prior to the engagement of said label with said container, means on said thread carrying member for preventing movement of said thread relative thereto during the movement thereof into engagement with said thread gripping member and for permitting relative movement of said thread and thread carrying member during return movement of the latter from engagement

- with said gripping member, means for severing said thread adjacent to the forward end of said thread carrying member at the end of said return movement, and means for lifting said thread carrying member at the end of said return movement to draw the thread taut between said thread carrying member and said thread gripping member.
4. In a machine for affixing a label to a container, a support for said container, a support for said label, means for imparting relative movement to said supports to affix said label to said container, and means for affixing an opening thread to said container comprising a spring closed thread gripping member, a movably mounted thread carrying member, fluid operated means for moving said thread carrying member between said container and said label into and out of engagement with said thread gripping member for inserting the thread therein prior to the engagement of said label with said container, electrically operated means for opening said thread gripping member, a knife movable across the end of said thread carrying member to sever said thread, and electrically operated means for moving said knife to thread cutting position.
5. In a machine for affixing a label to a container, a support for said container, a support for said label, means for imparting relative movement to said supports to affix said label to said container, and means for affixing an opening thread to said container comprising a spring closed thread gripping member, a movably mounted thread carrying member, fluid operated means for moving said thread carrying member between said container and said label into and out of engagement with said thread gripping member for inserting the thread therein prior to the engagement of said label with said container, electrically operated means for opening said thread gripping member, a knife movable across the end of said thread carrying member to sever said thread, electrically operated means for moving said knife to thread cutting position, and electrically operated means for raising said thread carrying member to take up slack in said thread prior to the opening of said thread gripping member and the cutting of said thread.
6. In a machine for affixing a label to a container, a support for said container, a support for said label, means for imparting relative movement to said supports to affix said label to said container, and means for affixing an opening thread to said container comprising a spring closed thread gripping member, a movably mounted thread carrying member, fluid operated means for moving said thread carrying member between said container and said label into and out of engagement with said thread gripping member for inserting the thread therein prior to the engagement of said label with said container, electrically operated means for opening said thread gripping member, a knife movable across the end of said thread carrying member to sever said thread, and electrically operated means for moving said knife to thread cutting position, electrically operated means for raising said thread carrying member to take up slack in said thread prior to the opening of said thread gripping member and the cutting of said thread, a valve for controlling said fluid operated means, switches for the respective electrically operated means, and a series of rotary cams for operating said valve and the respective switches.
7. In a machine for affixing a label to a container, a support for said container, a support for said label, means for imparting relative movement to said supports to affix said label to said container, and means for affixing an opening thread to said container comprising a spring closed thread gripping member, a movably mounted thread carrying member, fluid operated means for moving said thread carrying member between said container and said label into and out of engagement with said thread gripping member for inserting the thread therein prior to the engagement of said label with said container, electrically operated means for opening said thread gripping member, a knife movable across the end of said thread carrying member to sever said thread, and electrically operated means for moving said knife to thread cutting position, a valve for controlling said fluid operated means, and switches for the respective electrically operated means, and a series of rotary cams for operating said valve and the respective switches.
8. In a machine for affixing a label to a container, a mandrel for supporting said container, a supporting table for said label located beneath said mandrel and adapted to move upwardly to engage said label with said container, and means for affixing an opening thread to said container comprising a thread gripping member mounted on said table for adjustment thereon longitudinally of said mandrel, a thread carrying member mounted on said table for adjustment thereon longitudinally of said mandrel and for movement between said mandrel and said table in the lowered position thereof towards and away from said thread gripping member into and out of engagement therewith, means on said thread carrying member for preventing movement of said thread relative thereto during the movement thereof into engagement of said thread gripping member and for permitting relative movement of said thread and thread carrying member during the movement of the latter out of engagement with said thread gripping member, and means movable with and relative to said thread carrying member for severing said thread adjacent thereto at the end of the last mentioned movement thereof.
9. In a machine for affixing a label to a container, a mandrel for supporting said container, a supporting table for said label located beneath said mandrel and adapted to move upwardly to engage said label with said container, and means for affixing an opening thread to said container comprising a thread gripping member mounted on said table for adjustment thereon longitudinally of said mandrel, a thread carrying member mounted on said table for adjustment thereon longitudinally of said mandrel and for movement between said mandrel and said table in the lowered position thereof towards and away from said thread gripping member into and out of engagement therewith, means on said thread carrying member for preventing movement of said thread relative thereto during the movement thereof into engagement of said thread gripping member and for permitting relative movement of said thread and thread carrying member during the movement of the latter out of engagement with said thread gripping member, means movable with and relative to said thread carrying member for severing said thread adjacent thereto at the end of the last mentioned movement thereof, and means for raising said thread carrying member at said end of said movement, and means for

actuating said thread severing means after said raising movement.

10. In a machine for affixing a label to a container, a mandrel for supporting said container, a supporting table for said label located beneath said mandrel and adapted to move upwardly to engage said label with said container, and means for affixing an opening thread to said container comprising a thread gripping member mounted on said table for adjustment thereon longitudinally of said mandrel, a thread carrying member mounted on said table for adjustment thereon longitudinally of said mandrel, fluid operated means for moving said thread carrying member between said mandrel and said table in the lowered position thereof towards and away from said thread gripping member into and out of engagement with said thread gripping member, means on said thread carrying member for preventing movement of said thread relative thereto during the movement thereof into engagement of said thread gripping member and for permitting relative movement of said thread carrying member during the movement of the latter out of engagement with said thread gripping member and means movable with and relative to said thread carrying member for severing said thread adjacent thereto at the end of the last mentioned movement thereof, and electrically operated means for raising said thread carrying mechanisms at the end of such movement, and for moving said thread gripping means to thread receiving position.

11. In a machine for affixing a label to a container, a mandrel for supporting said container, a table for supporting said label beneath said mandrel, means for raising said table to engage said label with said container, and means for affixing an opening thread to said container comprising a thread gripping member and a thread carrying member, both mounted on and movable with said table, fluid operated means for moving said thread carrying means into and out of engagement with said thread gripping member in the lowered position of said table, means on said thread carrying member for preventing movement of said thread relative thereto during the movement thereof into engagement of said thread gripping member and for permitting relative movement of said thread and thread carrying member during the movement of the latter out of engagement with said gripping member, means for raising said thread carrying member at the end of such movement to take up slack in the thread between said thread carrying and gripping member, and means movable with said thread carrying member for severing the taut thread adjacent to said thread carrying member at said end of said movement thereof.

12. In a machine for affixing a label to a container, a support for said container, a support for said label, means for imparting the relative movement to said supports to affix said label to said container, and means for affixing an opening thread to said container comprising a thread gripping member and a thread carrying member movable between said container and said label into and out of engagement with said thread gripping member for inserting the thread therein prior to the engagement of said label with said container, means on said thread carrying member for preventing movement of said thread relative thereto during the movement thereof into engagement of said thread gripping member and

for permitting relative movement of said thread and thread carrying member during the movement of the latter out of engagement with said gripping member, means movable with said thread carrying member for severing said thread adjacent to said thread carrying member at the end of the last mentioned movement thereof, said means comprising a shearing edge formed on said thread carrying member and a movable member having a shearing edge adapted to cooperate with the shearing edge of said thread carrying member.

13. In a machine for affixing a label to a container, a support for said container, a support for said label, means for imparting the relative movement to said supports to affix said label to said container, and means for affixing an opening thread to said container comprising a thread gripping member and a thread carrying member movable between said container and said label into and out of engagement with said thread gripping member for inserting the thread therein prior to the engagement of said label with said container, means movable with said thread carrying member for severing said thread adjacent to said thread carrying member at the end of the movement thereof out of engagement with said thread gripping member, said means comprising a rock shaft movable with said thread carrying member, an arm fixed to said rock shaft, a knife mounted on the free end of said arm and adapted to move therewith across the forward end of said thread carrying member, means for normally holding said arm in inoperative position, and an electric solenoid for actuating said rock shaft to swing said knife carrying arm into cutting position.

14. In a machine for affixing a label to a container body, a support for said container, a support for said label, means for imparting relative movement to said supports to engage said label with said container, and means for affixing a thread to said container for rupturing said label, said means comprising a thread gripping member, a thread carrying member movable between said container and said label into and out of engagement with said gripping device to engage the thread therewith prior to the engagement of said label with said container, said thread carrying member comprising a main body portion, a block pivotally mounted on said main body portion for holding the thread down thereon, a spring for holding said block down on said main body portion, means for clamping the thread to said body portion only during the movement of the thread carrying member in the direction of the thread gripping member, and means for severing said thread in the retracted position of said thread carrying member.

15. In a machine for affixing a label to a container body, a support for said container, a support for said label, means for imparting relative movement to said supports to engage said label with said container, and means for affixing a thread to said container for rupturing said label, said means comprising a thread gripping member, a thread carrying member movable between said container and said label into and out of engagement with said gripping device to engage the thread therewith prior to the engagement of said label with said container, said thread carrying member comprising a main body portion, a block pivotally mounted on said main body portion for holding the thread down

thereon, a spring for holding said block down on said main body portion means for clamping the thread to said body portion only during the movement of the thread carrying member in the direction of the thread gripping member, and means for severing said thread in the retracted position of said thread carrying member, said means comprising a plate secured to the under side of said body member and projecting therebeyond to form a shearing edge, and a knife movable with said thread carrying member and adapted to swing across said shearing edge to sever the thread flush therewith, the projecting portion of said plate forming a supporting shelf for the loose end of said thread.

16. In a machine for affixing a label to a container body, a support for said container, a support for said label, means for imparting relative movement to said supports to engage said label with said container, and means for affixing a thread to said container for rupturing said label, said means comprising thread gripping jaws on said label support, a thread carrying member on said label support, fluid operated means on said label support for moving said thread carrying member between said container and said label into and out of engagement with said gripping jaws for entering the thread therebetween prior to the engagement of said label with said container, means on said thread carrying member for gripping the thread during the movement of said carrying member into engagement with said gripping jaws and for releasing said thread during the movement of said thread carrying member out of engagement with said thread gripping jaws, a spring for closing said jaws, and electric solenoid for opening said jaws, and an electric solenoid for raising said thread carrying member in the retracted position thereof to take up slack in said thread between said thread carrying member and said jaws.

17. In a machine for affixing a label to a container body, a support for said container, a support for said label, means for imparting relative movement to said supports to engage said label with said container, and means for affixing a thread to said container for rupturing said label, said means comprising a thread gripping member, a thread carrying member movable between said container and said label into and out of engagement with said gripping device to engage the thread therewith prior to the engagement of said label with said container, means for raising the forward end of said thread carrying member in the retracted position thereof for taking up slack in said thread beyond said end, said means comprising an electric solenoid having an armature cooperating with said thread carrying member, said thread gripping device comprising a pair of spring closed pivoted jaws, and an electric solenoid operatively connected to said jaws for opening the same to release the thread in the retracted position of said thread carrying member.

18. In a machine for affixing a label to a container body, a support for said container, a support for said label, means for imparting relative movement to said supports to engage said label with said container, and means for affixing a thread to said container for rupturing said label, said means comprising a thread gripping member, a thread carrying member movable between said container and said label into and out of engagement with said gripping device for inserting

the thread therein prior to the engagement of said label with said container, said thread gripping device comprising a pair of pivoted jaws, a rotary cam located between said jaws for opening the latter, a spring for closing said jaws, a shaft for rotating said cam, a pinion on said shaft, a rack meshing with said pinion, a spring for shifting said rack in one direction and an electric solenoid for shifting said rack in the opposite direction.

19. In a machine for affixing a label to a container body, a support for said container, support for said label, means for imparting relative movement to said supports to engage said label with said container, and means for affixing a thread to said container for rupturing said label, said means comprising a thread gripping member, a thread carrying member, fluid operated means for moving said thread carrying member between said container and said label into and out of engagement with said gripping device to engage the thread therewith prior to the engagement of said label with said container, a solenoid for raising said thread carrying member in the retracted position thereof to take up slack in said thread beyond said end, a knife for severing said thread at the forward end of said thread carrying member in the retracted position thereof, a solenoid for actuating said knife, said thread gripping device comprising a pair of pivoted jaws, a rotary cam located between said jaws for opening the latter, a spring for closing said jaws, a shaft for rotating said cam, a pinion on said shaft, a rack meshing with said pinion, a spring for shifting said rack in one direction and an electric solenoid for shifting said rack in the opposite direction.

20. In a machine for affixing a label to a container a rotary mandrel for supporting said container, a table for supporting said label below said mandrel, means for raising said table to engage the label thereon with the under side of said container and means for affixing an opening thread to said container comprising a thread gripping member mounted on said table, a thread carrying member mounted on said table and means for moving said thread carrying member between said mandrel and said table into and out of engagement with said thread gripping member in the lowermost position of said table.

21. In a machine for affixing a label to a container a rotary mandrel for supporting said container, a table for supporting said label below said mandrel, means for raising said table to engage the label thereon with the under side of said container and means for affixing an opening thread to said container comprising a thread gripping member mounted on said table, a thread carrying member mounted on said table, means for moving said thread carrying member between said mandrel and said table into and out of engagement with said thread gripping device in the lowermost position of said table, a shaft journaled on said table, a pair of arms depending from said shaft, a pair of levers pivotally supported intermediate between their ends on the respective arms, a cross bar connecting the mandrel opposing ends of said levers and supporting said thread carrying member, and means for actuating said shaft.

22. In a machine for affixing a label to a container a rotary mandrel for supporting said container, a table for supporting said label below said mandrel, means for raising said table to engage the label thereon with the under side of said container and means for affixing an opening thread

to said container comprising a thread gripping member mounted on said table, a thread carrying member mounted on said table, means for moving said thread carrying member between said mandrel and said table into and out of engagement with said thread gripping device in the lowermost position of said table, an upright frame removably secured to said table, a rock shaft journaled on said frame parallel with said mandrel, a pair of rock arms depending from said shaft, a pair of levers pivotally supported intermediate between their ends on the respective arms, a cross bar connecting the mandrel opposing ends of said levers and supporting said thread carrying member, means for actuating said shaft, plates removably secured to said table and having guide slots therein and rollers on the ends of said levers remote from their cross bar supporting ends and cooperating with the respective guide slots.

23. In a machine for affixing a label to a container a rotary mandrel for supporting said container, a table for supporting said label below said mandrel, means for raising said table to engage the label thereon with the under side of said container and means for affixing an opening thread to said container comprising a thread gripping member mounted on said table, a thread carrying member, means for moving said thread carrying member between said mandrel and said table into and out of engagement with said thread gripping member in the lowermost position of said table, an upright frame removably secured to said table, a shaft journaled on said frame parallel with said mandrel, a pair of arms fixed to said shaft, a pair of levers disposed transversely of said mandrel and pivotally supported intermediate between their ends on the lower end of the respective arms, a cross bar connecting the mandrel opposing ends of said levers and supporting said thread carrying member, fluid operated means for actuating said shaft, plates removably secured to the respective frames and having guide slots therein, and rollers on the ends of said levers remote from their cross bar supporting ends and cooperating with the respective cam slots.

24. In a machine for affixing a label to a container a rotary mandrel for supporting said container, a table for supporting said label below said mandrel, means for raising said table to engage the label thereon with the under side of said container and means for affixing an opening thread to said container comprising a thread gripping device mounted on said table, an electric solenoid for actuating said gripping member, a thread carrying device, means for moving said thread

carrying device between said mandrel and said table into and out of engagement with said thread gripping device in the lowermost position of said table, an upright frame removably secured to said table, a rock shaft journaled on said frame parallel with said mandrel, a pair of rock arms depending from said shaft, a pair of levers disposed transversely of said shaft and pivotally supported intermediate between their ends on the respective rock arms, a cross bar connecting the mandrel opposing ends of said levers and supporting said thread carrying device, a fluid cylinder mounted on said frame for actuating said rock shaft, plates removably secured to said table and having guide slots therein having their mandrel opposing ends extending upwardly and their other ends extending downwardly, rollers on the ends of said levers remote from their cross bar supporting ends and cooperating with the respective guide slots, an electric solenoid for drawing said rollers into said downwardly extending ends of said slots, a thread cutting device mounted on said cross bar, an electric solenoid for operating said thread cutting device, a valve for controlling said fluid cylinder, electric switches for controlling the respective solenoids, and cams for operating said valve and switches.

25. In a machine for affixing a label to a container, a mandrel for supporting said container, a table for supporting a stack of labels below said mandrel, means moving said table upwardly to press the label out the top of said stack against the under side of a container on said mandrel, and means for affixing a thread to said container for rupturing said label, said means comprising a thread gripping member mounted on said table, and a thread carrying member mounted on said table and movable between said container and said stack into and out of engagement with said gripping device for engaging the thread therewith prior to the engagement of said label with said container, the thread engaging portion of said thread gripping device being disposed above the top of said stack in the lower position of said table and being adapted to move downwardly below the top of said stack when the table moves upwardly to press said stack against the underside of said container.
